[57] CLAIM

The ornamental design for an air deflector for trailers, as shown and described.

DESCRIPTION

FIG. 1 is an isometric view of an air deflector for trailers embodying our new design;

FIG. 2 is a side elevational view thereof, the opposite side being a mirror image of the side shown herein;

FIG. 3 is a front elevational view thereof;

FIG. 4 is a top plan view thereof;

FIG. 5 is a bottom plan view thereof.

The fragmentary broken line showing of the trailer in FIGS. 2-5 is for illustrative purposes only.

FIG. 1.

FIG. 2.

FIG. 4.

FIG. 3.

FIG. 5.
